UNITED STATES PATENT OFFICE.

WILLIAM P. DUN LANY, OF CHICAGO, ILLINOIS, ASSIGNOR TO SEARS, ROEBUCK AND CO., OF CHICAGO, ILLINOIS, A CORPORATION OF NEW YORK.

DOLL OR THE LIKE.

1,293,056.

Specification of Letters Patent.

Patented Feb. 4, 1919.

Application filed February 5, 1918. Serial No. 215,471.

To all whom it may concern:

Be it known that I, WILLIAM P. DUN LANY, a citizen of the United States, residing at Chicago, in the county of Cook and 5 State of Illinois, have invented certain new and useful Improvements in Dolls or the like, of which the following is a specification.

This invention relates to dolls or like 10 figures and the general object of the invention is to provide a novel and improved means for securing the head and the limbs to the torso.

A special object is to provide improved 15 means for attaching the arms and legs in a manner which is firm and secure and yet allows rotative adjustment thereof with respect to the torso as well as swinging movement toward and from the torso.

20 Another object is to provide improved means for securing the head or neck section to the torso in a manner allowing the said section to be adjusted into different rotative and angular positions with respect to 25 the torso.

A further object is to provide securing means for the limbs and head which is especially adapted for use with dolls or the like made of hardened plastic material.

30 Further objects and advantages relating to specific features of construction will be fully understood from a perusal of the following description.

In the accompanying drawings, Figure 1 35 is a front elevation, partly in section, of a doll or like figure embodying the features of my invention, portions of the arms and head being broken away and the legs being removed from the torso. Fig. 2 is an enlarged fragmental view with the arm-securing 40 means shown in section. Fig. 3 is a view showing a fragment of the torso and the thigh portion of one of the legs, said parts being sectioned away to illustrate the 45 securing means in elevation. Fig. 4 is an elevational view of one of the elements for securing a limb to the torso. Fig. 5 is a section on line 5—5 of Fig. 4 looking in the direction of the arrows. Fig. 6 is an elevational view of the complementary securing 50 element, and Fig. 7 is a section on line 7—7 of Fig. 6 looking in the direction of the arrows. Fig. 8 is an elevational view of the sleeve which forms part of the means for 55 locking the elements together.

For the sake of imparting a full and clear understanding of the particular embodiment of my invention which I have selected for purposes of illustration, I will herein describe the said embodiment in detail, but it 60 should be understood that I do not thereby intend in any way to limit my invention, the scope of which will be pointed out in the appended claims.

In the present embodiment, the doll is 65 made of plastic material molded to a form simulating a small baby, the torso and also the limbs and head being made hollow, the material used being such that it becomes very hard when dry. The torso is indicated by 70 reference numeral 10. 11 designates the arms, 12 one of the legs and 13 the head or neck section.

The means herein shown for securing each limb to the torso comprises two elements 14 75 and 15 which are arranged to be secured respectively to the limb and the torso. The element 14 consists of a single member formed wholly of sheet metal and comprising a flat base or disk portion 16 and a 80 flared or conical securing portion 17. The disk portion 16 has a central hole or socket 18 preferably surrounded by an annular inwardly extending rim member or flange 19, and the securing portion 17 extends inwardly from the disk portion and is embedded in the material of the limb. The element 14 is preferably so positioned in the limb that the outer face of the disk portion 16 projects slightly beyond the bearing face 90 of the limb, and preferably the securing portion 17 has suitable ribs 20 and notches 21 formed therein in order that it will interlock with the embedding material and thus firmly hold the element in position in the limb. 95

The element 15 which is arranged to be mounted in the torso has a member similar to the element 14 embedded in the material of the torso just as the member forming the element 14 is embedded in the material of 100 the limb. Said member is formed of sheet metal and comprises a flat base or disk portion 16^a having a central hole or socket 18^a and a flared or conical securing portion 17^a having ribs 20^a and notches 21^a. Preferably 105 said element has an annular outwardly extending rim member or flange 22 adapted to pass through the socket 18 of the element 14.

The element 15 also comprises means arranged to yieldingly engage with the element 110

14 and lock the two elements together so as to permit relative rotation thereof and also a swinging of the limb toward and from the torso. Such means consists of a tubular projection or sleeve 23 and a compression spring 24. The sleeve is entered through the socket 18^a and is provided at each end with outwardly extending shoulders such as peripheral flanges 25 and 26; 10 and the spring 24 surrounds said sleeve and bears between the flange 25 on the inner end of the sleeve and the inner face of the disk portion 17^a. The sleeve thus extends inwardly from the disk portion 17^a with the 15 flange 26 on the outer end of the sleeve bearing against the end of the annular rim member 22 projecting outwardly from said disk portion.

At least one of the elements is sufficiently 20 resilient to permit the flange 26 on the outer end of the sleeve 23 to spring through the socket 18 of the element 14 and into locking engagement with the inner end of the annular rim member 19. For this purpose, the 25 socket element 14 is in the present instance provided with radial slots 27 communicating with the central aperture to increase the resiliency; and to facilitate the insertion of the flange 26 on the outer end of the 30 sleeve 23 through the socket 18^a of the element 15, as well as to enable said flange to be readily sprung through the socket 18 of the element 14, said sleeve is preferably provided throughout its length with a slit 28.

35 It will be apparent that the spring 24 permits the sleeve to swing laterally relative thereto in any direction, and in order to permit of such swinging motion of the limb toward and from the torso, the sleeve is 40 preferably made somewhat smaller in diameter than the diameter of the sockets 18 and 18^a. Furthermore, the slit 28 in the sleeve 23 enables the sleeve to be compressed slightly by its engagement with the walls of 45 the sockets 18 and 18^a in such swinging movement of the limb, and thus the resiliency of the sleeve serves to increase the extent of swinging movement of the limb.

In securing the limb to the torso, the limb 50 is simply pressed toward the torso with sufficient force to pass the sleeve 23 through the socket 18 and cause the socket flange 19 to engage behind the flange 26 on the sleeve. The two elements 14 and 15 will then be 55 securely and permanently interlocked but with allowance for relative rotation and also a swinging motion toward and from the torso. Thus the limb may be moved relative to the torso in all directions.

60 The upper end of the torso has a central socket to receive the lower end of the head or neck section 13 and allow either rotative or angular movement of the latter. The head or neck section is held in the socket by 65 yieldable means which in the present in-

stance comprises a coiled compression spring 29 within the said section, said spring being rotatably insertible thereinto through an opening 30 in the lower end of the section, and the spring being of larger diameter 70 than said opening so that it will be prevented from accidental escape downward through the opening. To the upper end of the spring is attached a connecting member or link 31 which preferably has a swivel connection with the spring as by forming an eye 32 on the end of the spring through which eye the link passes to the limit allowed by a stop 33 on the upper end of the link. The link passes down centrally 80 through the spring and through the opening 30 and has a hook or loop 34 on its lower end. An anchor rod 35 passes transversely through the torso and the hook 34 engages said rod. It will be seen that the head or 85 neck section will be yieldingly secured to the torso no matter what position of rotative or angular adjustment the head may occupy. The swivel joint 32, 33 contributes to the flexibility of the connection. 90

The ends of the anchor rod 35 pass through the central openings in the arm-securing elements 14 and 15 and disengagement of either end from the securing elements is prevented in the present instance 95 by making the rod of such length that its ends extend into the arms a sufficient distance so that escape of either end is made impossible by reason of the abutment of the opposite end of the rod with the adjacent 100 wall of one of the arms 11.

In assembling the head section with the torso, after the spring 29 has been inserted into said section and after the anchor rod 35 has been inserted through the torso, the 105 hook 34 may be engaged with said anchor rod by drawing the hook downwardly to compress the spring 29, whereby the hook may be engaged with the rod by a pair of pliers before the neck is seated in its socket. 110 When released, the spring 29 will then draw the neck down into the socket. The arms 11 may be secured to the torso after the anchor rod is in place and either before or after the head section has been mounted. 115

The securing elements for the legs and the flat faces which surround said securing elements are located in planes which converge forwardly and downwardly and the axes of rotative adjustment of the legs are 120 at right angles to such planes. Numerous and quite different postures and effects may be accomplished by changing the limbs and head or neck section to varying positions. A manufacturer may provide a variety of 125 designs of dolls by using a standard shape of torso and attaching thereto limbs and heads of different shapes. My improved securing means is very advantageous from a practical standpoint because of its cheap- 130

ness of manufacture, security of its hold and adjustability.

I claim as my invention:

1. A doll or the like having, in combination, a torso having a flat face, a limb having a correspondingly flat face, said torso and limb being formed of hardened plastic material, and means for securing the limb to the torso comprising two elements having portions embedded respectively in the hardened material of the limb and the torso so as to be held thereby at said faces, one of said elements having a socket and the other element having a sleeve movable relative thereto and arranged to engage in said socket, at least one of the elements having a yieldable portion to allow such engagement and hold the sleeve in the socket when associated, the axis of the sleeve and socket being normally perpendicular to said flat faces on the limb and the torso, and the limb being laterally swingable and rotatably adjustable about such axis.

2. A doll or the like comprising, in combination, a torso, a pair of arms, said torso and arms being formed of hardened plastic material, means for securing each arm to the torso comprising two elements having portions embedded respectively in the material of the arm and the torso, one of said elements having a socket and the other element having a sleeve movable relative thereto and arranged to engage in said socket and allowing rotatable and lateral adjustment of the arm, a transverse anchor rod in the torso having its opposite ends engaging the respective securing means for the arms, a head or neck section, and means engaging said anchor rod for securing said head or neck section to the torso.

3. A doll or the like having, in combination, two sections and means for securing said sections together and permitting a swinging movement therebetween comprising two elements secured to the respective sections, one of said elements having a socket, and the other of said elements having a sleeve with a flanged end and a compression spring for holding the flanged end of said sleeve interengaged with the socket of the first mentioned element.

4. A doll or the like having, in combination, two sections, and means for securing said sections together and permitting a swinging movement therebetween comprising two elements secured to the respective sections, one of said elements having a socket, and the other of said elements having a sleeve and a spring for holding one end of the sleeve interengaged with the socket of the first mentioned element.

5. A doll or the like having, in combination, two sections, and means for securing said sections together and permitting a swinging movement therebetween comprising

ing two elements secured to the respective sections, each of said elements having a bearing disk with a socket, and one of said elements having a sleeve with flanged ends entered through the sockets of both elements and a compression spring bearing between the flange at one end of the sleeve and the bearing disk of the element and holding the flange at the other end of the sleeve interengaged with the socket of the first mentioned element.

6. A doll or the like having, in combination, two sections, and means for securing said sections together and permitting relative rotative and also lateral movement therebetween comprising two elements secured to the respective sections and having flanges adapted to be sprung into engagement with each other, one of said flanges being yieldingly held interengaged with the flange of the other element.

7. A doll or the like having, in combination, two sections, and means for securing said sections together and permitting relative rotative and also lateral movement therebetween comprising two elements secured to the respective sections, one of said elements having a flange thereon yieldingly held interengaged with the other element and at least one of said elements being resilient to permit such interengaging of the elements.

8. A doll or the like having, in combination, two sections and means for securing said sections together and permitting relative rotative and also lateral movement therebetween comprising two elements secured to the respective sections, one of said elements having a resilient sleeve yieldingly held interengaged with the other element.

9. A doll or the like, having, in combination, two sections, and means for securing said sections together and permitting relative rotative and also lateral movement therebetween comprising two elements secured to the respective sections, one of said elements having a resilient sleeve arranged to be sprung into holding engagement with the other element.

10. A doll or the like having, in combination, two sections and means for securing said sections together and permitting relative movement therebetween comprising two elements secured to the respective sections, one of said elements having a sleeve arranged to be sprung into holding engagement with the other element, said sleeve having a longitudinally extending slit therein to make it resilient.

11. A doll or the like having, in combination, a torso, a pair of arms, means for securing each of said arms to the torso to permit rotative as well as lateral swinging movement including an element having a sleeve, a separate head section, and means

for securing said head section to the torso including a rigid transverse anchor rod having its opposite ends bearing in the sleeve of each of said arm-securing means.

5 12. A doll or the like having, in combination, two sections, and means for securing said sections together and permitting relative movement therebetween comprising two elements secured to the respective sections, 10 one of said elements having a socket and the

other of said elements having a projection engaging in said socket to hold the elements interengaged, said projection being movable rotatively and also longitudinally relative to the socket to permit the swinging of one section relative to the other in any direction. 15

In testimony whereof, I have hereunto set my hand.

WILLIAM P. DUN LANY.
